(57) **CLAIM**

I Claim the ornamental design for a shoe sole, as shown and described.

DESCRIPTION

The present invention is a blind shoe sole design.

FIG. 1 is a bottom plan view of a shoe sole of the present invention;

FIG. 2 is a right side elevational view thereof;

FIG. 3 is a left side elevational view thereof;

FIG. 4 is a front elevational view thereof; and,

FIG. 5 is a rear elevational view thereof.

The broken lines shown in the drawings are for illustrative purposes only and form no part of the claimed design.

The broken lines shown in the drawings, including the repeated lines in the toe portion of the shoe sole, are for illustrative purposes and form no part of the claimed design.
